UNITED STATES PATENT OFFICE.

EMIL WEIBEL, OF MONTREAL, QUEBEC, CANADA.

HARNESS FRAME.

Application filed April 24, 1926. Serial No. 104,379.

This invention relates to heddle-frames characterized by top and bottom wooden rails to which are attached heddle bars (lying in the same plane as and between the rails) on which the heddles are strung. Heretofore the rails have been rigidly connected, usually by flat metal side strips each of which bears against the end faces of and is secured fast to the two rails, so that they form with the rails a rigid frame. The presence of these strips adds considerably to the weight of the heddle frame, and they also contribute to make it impossible to reduce the thickness of the heddle-frame beyond a certain limit, since their screws or other securing means have to be accommodated and for that purpose the wooden rails have to have a certain thickness in order to receive and properly support the screws. According to this invention instead of rigidly connecting the two rails, or in fact connecting the rails directly at all, I provide link members which connect the mentioned heddle bars. Since these link members may be suitable lengths of wire properly fashioned to function as links it is possible by their use to greatly reduce the weight of the heddle frame and also to appreciably reduce its thickness.

In the drawings,

Fig. 1 is a front elevation of a heddle frame embodying the present invention;

Fig. 2 is a side elevation showing the structure including the lower rail and heddle bar removed;

Fig. 3 is a similar view of the upper rail and heddle bar;

Fig. 4 is a fragmentary front elevation showing a modification of the invention;

Fig. 5 is a sectional view on line 5—5 of Fig. 4; and

Fig. 6 is a sectional detail of a part of the invention as shown in Figs. 1 to 3; and

Fig. 7 is a fragmentary view of the frame, illustrating the modified form of the device by which each heddle bar is attached to the corresponding rail.

1 1 designate the upper and lower rails, which may be of wood, as usual. 2 2 designate the upper and lower heddle bars for the two rails, they being as usual strips of metal. 3 designates devices by which each heddle bar is attached to the corresponding rail. Following the usual construction these are hooks which are screwed into the rails at their relatively inner edges at spaced points and receive in their hooked portions the heddle bars. 4 designates the heddles threaded on the heddle bars, which may be either wire heddles or heddles formed of flat sheet material. The heddles must have freedom to shift laterally, or lengthwise of the heddle bars, on which they are shown as mounted in the usual way by being penetrated at their ends by said bars, which shifting is made possible in the ordinary rigid type of frame which I have already described by spacing the heddle bars 2 2 a trifle closer together than the heddles themselves would permit.

5 indicates the mentioned links by which each structure including a rail, a heddle bar and the devices 3 by which the heddle bar is attached to the rail is connected to the other said structure. In Figs. 1, 2 and 3 each of these links is formed of a strip of wire having its ends 6 returned or rebent to form hooks, there being also a bend preferably at 7 adjoining the hook thus formed so that the bight or space of the hook lies in the same plane as the straight body part of the link. Preferably in this form of the invention this bight or space 8 is about as wide as each heddle bar is thick, and the length of the hook somewhat exceeds the distance between the heddle bar and the rail. There may be as many links as the length of the frame and the number and consequently the weight of the heddles therein may require, but in any event there will be one at each end of the heddle frame. The links are hooked over the heddle bars as shown in Figs. 1 and 2 and the effective length of each link is such that the weight of the lower structure formed by parts 1, 2 and 3 is assumed by the links and not by the heddles, which are thus free to shift laterally.

To prevent the end links from slipping lengthwise of the heddle bars the latter may be equipped with suitable stops arranged relatively outwardly of the links and so as to coat for this purpose with the hooks 3 inward of and adjoining the links. In the present case these stops are formed by split rings 9 penetrating holes 10 in the ends of the heddle bars.

Since the length of the rebent or return portion of each link exceeds the distance between the corresponding element 2 and the abutment for the link afforded by the adjoining rail it will be seen that the links cannot be accidentally separated from the

5 heddle bars by lengthwise movement (as when the frame is being handled out of the loom) because they are opposed in such movement by the rails. Therefore for attaching any hook to or removing it from a heddle bar in the construction shown in Figs. 1, 2 and 3, the link is shifted to the position shown by dotted lines in Fig. 2, springing the hooks open, which will position the hook so as to clear the rail on lengthwise movement.

10 In the modified form of the invention shown in Figs. 4 and 5 the construction is substantially the same as that shown in Figs. 1, 2 and 3 excepting that I eliminate the necessity for stops, such as 9, by providing holes 11 in the heddle bars to receive the hooks 6 of the links.

15 Reducing the thickness of the heddle frame may be augmented by employing flattened material, as shown, for the devices 3 and the links.

20 For preventing lateral shifting of the connectors 5 the construction shown in Fig. 7 may be used. Here the eyed or hook-portion 25 of the device 12, corresponding to device 3 in the other figures, is split in a plane cutting the heddle bar and receives the connector 5 in its split.

Having thus fully described my invention 30 what I claim and desire to secure by Letters Patent is:

1. A heddle frame comprising, in combination, with upper and lower structures each including a horizontally elongated heddle-supporting element and said upper and lower structures also including abutments close to and respectively above and below such elements thereof, links each having its ends formed with return portions and thus 40 hook-shaped, the hooks of each link respectively receiving said elements and each return portion thereof having a length exceeding the distance between the corresponding element and abutment. 45

2. A heddle frame including upper and lower horizontal structures one of which includes a horizontal rail, a horizontal heddle-bar and an eyed device attached to the rail and receiving the bar in its eye, and a 50 connector extending from one to the other structure and engaged with said bar, said eyed device being split in a plane cutting the heddle bar and receiving the connector in its split. 55

In testimony whereof I affix my signature.

EMIL WEIBEL.
